SCOURING PAD AND METHOD OF MAKING

William H. Robbins, Springfield, Ohio, assignor
to The Williams Company, London, Ohio, a
corporation of Ohio

Application January 5, 1932. Serial No. 584,837

2 Claims. (Cl. 15—209)

This invention relates to improvements in scouring pads and the method of making them, and has for its object to provide a pad composed of steel wool in which there is a strip 5 or ribbon of steel wool strands, and from this strip or ribbon to form of continuous steel wool strands a pad by forming the ribbon into a plurality of arcuate layers, each layer being connected to an adjacent and oppositely disposed 10 layer so that the attaching parts of these layers form an acute angle with each other. These layers increase in size progressively from the center of the pad to the outer periphery of the pad.

15 In making the pad the strip is rolled into a compact cylindrical body, and thereafter pressed so that the original cylindrical body is formed into a double convex solid with arcuate sides and sharp edges.

20 A preferred embodiment of this invention is shown in the drawing.

Referring to the drawing:

Figure 1 shows a strip or short piece of ribbon composed of a plurality of continuous strands of 25 steel wool compactly arranged.

Figure 2 shows the strip shown in Figure 1 rolled into a compact cylindrical mass.

Figure 3 shows an end view of the pad compressed into a double convex form, with oppositely disposed arcuate sides and oppositely disposed sharp edges.

Figure 4 shows an end view of the pad shown in Figure 3 after it has been used, with the two used layers folded back upon the opposite side, 35 and serving as a handhold.

Figure 5 is a perspective view of the pad shown in Figure 4.

In Figure 1 a section 1 of a short strip or piece of steel wool ribbon is shown. This strip is composed of a plurality of longitudinally arranged strands of steel wool. These strands are cut into very fine threads, and are maintained in a continuous condition so that there is no disposition to break up into fine detached sections.

40 The sizes of these strands, as commonly used for the formation of the present pad, are .0003 inch, .0005 inch, .00065 inch, .001 inch, .005x.002 inch, .002x.0026 and .003x.0055 inch. All the strands are in a long unbroken and uniform condition so that they are not likely to break and crumble, and become useless.

45 While the strands are continuous and unbroken, yet each strand assumes an irregular and waving condition, thereby cooperating with 50 all the other strands to form a compact pad, in

which each strand performs its part in maintaining the pad in a compact condition, as shown in Figure 1. The irregular course followed by any particular strand is illustrated in Figure 1 by the reference numeral 2. This numeral is 60 found in Figure 1 in three places, and in each place designates the same strand as located in different positions on the strip. It will be observed that the strand is continuous but irregular in its lateral position.

65 After the strip has been formed, as shown in Figure 1, it is rolled upon itself spirally to form a cylindrical pad, as indicated in Figure 2. The pad as shown in Figure 2 is compressed on opposite sides so that two other opposite sides are 70 forced outwardly. In forcing the two sides together there is formed a pad built up of a series of concavo-convex layers 3, increasing in size from the center toward the lateral surfaces in both directions. These concavo-convex layers 75 are united to each other at their ends to form with each other acute angles or corners, as indicated by the numeral 4.

The method of forming the steel wool pad comprises arranging the strands of loose steel 80 shavings longitudinally with the strands extending substantially in the same direction as shown in Fig. 1. The strands are then compressed to form a compact ribbon having its upper and lower surfaces in compressed condition, after 85 which the ribbon is rolled to form a round pad. The round pad is subsequently compressed to form a plurality of opposed definite layers with inner concave and outer convex surfaces and with adjoining edges forming acute angles, as 90 shown in Fig. 3.

The article comprises a pad formed of a plurality of longitudinally arranged strands of steel shavings made into a single compressed steel wool ribbon spirally wound, which has been compressed to the extent to allow unwinding after use, the pad as formed having a plurality of opposed defined layers, each layer having a concave inner surface and a convex outer surface. The completed abrasive pad is thus formed with 95 each layer, except the two forming the terminals of the ribbon, being connected on opposite edges at an acute angle to the edges of adjacent layers similarly formed and on the opposite side of the pad. The convex and concave surfaces of 100 the layers are so compressed prior to winding as to permit the layers to be folded back upon themselves to present unused surfaces to the article worked upon, as shown in Figs. 4 and 5 of the drawing.

100

105

110

When the pad is completely formed, as shown in Figure 3, each strand of steel wool extends from the free end of the strip on one side of the pad to the other end of the strip located 5 within the center of the pad. In order to use the pad the upper part thereof is gripped by the hand 5 of the operator, somewhat as shown in Figure 4.

After a layer has been used for polishing and 10 dusting purposes, a certain amount of dust and worn-away material accumulates in the strands. When the accumulation of foreign material becomes sufficient to destroy the efficiency of the pad the worn layer 6 of the pad is rolled back 15 upon the other side, as shown in Figures 4 and 5. This folded-back part is used as a handhold and a clean surface is provided for polishing purposes. This surface is just as fresh and 20 clean as the pad originally was before it had been used.

When the under layer, as shown in Figure 4, becomes clogged with worn-off material and 25 dust, the upper three layers are bent downwardly underneath the lower layer, as shown in Figure 4, after which the whole pad is reversed, and what has been the fourth layer from the top in Figure 4 becomes the lower or new layer 30 for brushing, scrubbing and cleaning purposes. By this successive unfolding the whole pad may 35 be used, and the pad at the last is just as fresh and capable of doing just as efficient polishing and rubbing as it was when it was first formed, because the polishing surface is new, not having been previously used.

Since the strands are continuous no frazzled 40 ends and broken-off strands are left on the work. These strands will not litter the material being polished, will not get on the clothes and hands of the operator as if the steel wool 45 strands were formed into a ball in which they were promiscuously arranged.

In the present pad the polishing surface consists of the parts of the strands intermediate 50 their ends. The whole under surface of the pad, as shown in Figure 4, may be used for 55 polishing purposes, and when this whole sur-

face has become clogged with worn-off material this layer is covered up by the three upper layers, as shown in Figure 4. The three upper layers being removed, expose a clean and new 60 polishing layer, new in the sense that it has not been used nor contaminated by the fact that the other layers have been used.

It will be understood that I desire to comprehend within my invention such modifications as 65 come within the scope of my claims and my invention.

Having thus fully described my invention, what I claim as new and desire to secure by Letters Patent, is:

1. An article of manufacture for use as an 70 abrasive, comprising a pad formed of a plurality of longitudinally arranged strands of steel shavings and made into a single compressed steel 75 wool ribbon spirally wound which has been compressed to the extent to allow unwinding after use, said pad having a plurality of opposed defined layers each having a concave inner surface and a convex outer surface, each layer except the two forming the terminals of said ribbon being connected on opposite edges at an 80 acute angle to the edges of adjacent layers similarly formed and on the opposite side of the pad, the convex and concave surfaces of said 85 layers being so compressed prior to winding to permit the layers to be folded back upon themselves to present unused surfaces to the article 90 worked upon.

2. A method of forming a steel wool pad, comprising arranging strands of loose steel shavings, 95 longitudinally, with the strands extending substantially in the same direction, compressing the strands to form a compact ribbon, having its upper and lower surfaces in compressed condition, rolling the ribbon from one end to the other to form a round pad, and subsequently 100 compressing the pad and forming a plurality of defined layers with inner concave and outer convex surfaces and with joining edges 105 forming acute angles.
